Des. 653

Jacob Beesley & Edward J. Delany of Philadelphia, Pa.

Assignors to

Breson, Stewart, & Peterson, of same place.

Letters Patent No. 653. Dated May 23d, 1854.

The schedule referred to in these Letters Patent, & making part of the same.

To all whom these presents shall come:

Be it known that we, Jacob Beesley and Edward J. Delany, of Philadelphia, in the county of Philadelphia, and State of Pennsylvania, have invented a new design for a Parlor Stove, and that the following is a full, clear, and exact description of the principle or character which distinguishes it from all other things before known, and of the usual manner of making, modifying, and using the same; reference being had to the accompanying drawings.

Fig. 1 is a front or face view of the front plate illustrating the door.

Fig. 2 is a side view of the end plate.

Fig. 3 is a top view of the top plate.

Fig. 4 is a front view of the bottom plate illustrating the hearth plate and ventilator.

These drawings illustrate our design for the Gothic Queen Parlor Stove, other parts of the stove being plain & ornamental at pleasure.

What we claim as our invention is, the design for the Gothic Queen Parlor Stove, as herein above illustrated and set forth.
